O. M. Clarke
ATTORNEY

UNITED STATES PATENT OFFICE.

CHARLES ALSNAUER, OF FARRELL, PENNSYLVANIA.

OPENING MACHINE FOR SHEET METAL.

Application filed October 11, 1922. Serial No. 593,699.

To all whom it may concern:

Be it known that I, CHARLES ALSNAUER, a citizen of the United States, residing at Farrell, in the county of Mercer and State of Pennsylvania, have invented certain new and useful Improvements in Opening Machines for Sheet Metal, of which the following is a specification.

My invention consists of an improvement in opening machine for tin plate stickers. In the art of rolling thin sheet metal in packs or multiple layers, there frequently occur "stickers," i. e., where two adjacent sheets are stuck together. Ordinarily, these are separated by hand, involving laborious, tedious and costly operations, as well as tending to deformation of the sheets.

In my invention, I utilize a pair of rolls and a dividing or separating knife, over and under which the stuck sheets are drawn by the rolls, in the manner hereinafter described.

In the drawings:

Fig. 1 is a sectional elevation of the machine on the line I—I of Fig. 2;

Fig. 2 is a plan view of the machine;

Figs. 3 and 4 are detail views showing the action of the rolls.

In the drawings, 2 is a supporting frame preferably mounted on castors 3 for easy movement over a floor, and provided with a table 4—5, preferably at varying levels, as shown. At each side of the table are housings 6—6 in which are mounted rolls 7—7, and provided with suitable adjusting mechanism for varying the distance between the rolls, as is usual in rolling mills.

The rolls are geared together for rotation in opposite directions, as indicated by the arrows, by gearing 8 and are driven by a reversible motor 9 through gearing 10, or other suitable means.

Immediately in front of the roll pass is a transverse knife blade 11 fixedly mounted between the housings, with its sharp edge extending away from the pass and its rear

edge spaced away from the roll contours sufficiently to provide re-entrant clearance for the sheets after separation.

In operation, a pair of stuck sheets 12—12 are first separated by hand at their edges and sufficiently far back to admit of insertion over and under the knife 11 and into the grip of the rolls 7. Thereafter, as the sheets are pushed over table 4, which is just below the knife 11, the bite of the rolls will draw the sheets forwardly over the knife blade, effecting complete and rapid separation, the two separated sheets passing onwardly between the rolls and out onto the lower receiving table 5 beyond. The action of the rolls on the sheets tends to flatten and smooth any wrinkles or bends leaving them in good merchandizable condition.

The machine is very simple and cheap in construction, may be used for various sizes of sheets, and may be moved around to various points in the mill for use on accumulated piles of stickers.

What I claim is:

1. A separating machine for sheet metal consisting of a pair of rolls and a thin separating knife located immediately in advance of the roll pass.

2. A separating machine for sheet metal consisting of a pair of rolls, means for driving the rolls together, a thin separating knife having an outwardly directed edge located in advance of the pass of the rolls, and a feeding and receiving table at each side of the rolls respectively.

3. A separating machine for sheet metal consisting of a supporting frame provided with a table and housings at each side, a pair of rolls therein, gearing and means for driving the rolls together in opposite directions, and a thin separating knife in advance of the pass of the rolls and mounted by its ends on the housings.

In testimony whereof I hereunto affix my signature.

CHARLES ALSNAUER.
